CLAIM

The ornamental design for a process data recorder for injection molding processes, as shown and described.

DESCRIPTION

1.-2. Process data recorder for injection molding processes

1.1 : Front

1.2 : Back

1.3 : Right

1.4 : Left

1.5 : Top

1.6 : Bottom

1.7 : Perspective

1.8 : Perspective

1.9 : Perspective

1.10 : Perspective

2.0 : Perspective

The broken lines depict unclaimed environmental subject matter.
